PATTERN GRADING MACHINE

George F. Ryan, Lynn, Mass., assignor, by mesne assignments, to United Shoe Machinery Corporation, Paterson, N. J., a corporation of New Jersey

Application March 3, 1930, Serial No. 432,866

57 Claims. (Cl. 33—23)

This invention relates to pattern reproduction and is disclosed as embodied in a pattern grading machine for cutting shoe upper patterns, of the type shown in United States Letters Patent No. 1,079,022, issued November 18, 1913, on the application of C. E. Reed. While the invention has been described in relation to a pattern grading machine it is not necessarily limited to machines of this type, or even to two-dimensional as distinguished from three-dimensional machines.

A pattern reproducing machine contains two pantographs which geometrically magnify the length and width of the model independently. That is, all lines drawn in the model pattern parallel to its length are multiplied in length by a constant, and all lines drawn in it parallel to its width are multiplied in length by an independent constant, and reproduced in the work. A shoe upper part cut from a pattern so graded from a model pattern will fit a last graded in the ordinary manner in a last lathe. Such lasts are, however, unsatisfactory, particularly in the manufacture of women's shoes, because of the intolerable variations in toe spring introduced by the width grader and they have to be "bent" back to a satisfactory shape by sawing opposite slots and wedging one until the other closes, or by cutting a corrected last directly in a special lathe, such as is shown in United States Letters Patent No. 1,362,183, issued December 14, 1920, on the application of L. B. Whipple, or in United States Letters Patent No. 1,362,185, issued December 14, 1920, on the application of S. E. Boynton. Such corrected lasts cannot be fitted by uppers graded in the ordinary way, and it has been necessary to improve the pattern grading machine so that it will in effect bend the model or, in another way of looking at the matter, reproduce from it a bent work piece. This problem has been treated in United States Letters Patent No. 1,520,075, issued December 23, 1924, on the application of R. M. Packard, and No. 1,807,195, issued May 26, 1931, on the application of E. H. Burke.

Pattern copying machines of either of the two types mentioned, that is, for reproducing solid or flat patterns, comprise four primary instrumentalities, model holder, work holder, model follower and tool, interconnected by pantographic mechanism, whereby the movement of the follower around the pattern controls the movement of the tool around the work. These movements are to be considered as relative movements, because it is unnecessary that all of the instrumentalities actually move. In the last lathe they all move:

in the pattern grading machine the model and work are normally motionless.

For the purpose of dealing with the problem described above, all four of the machines of the patents and applications mentioned embody the same fundamental principle. In each a movement of a primary instrumentality, in addition to that characteristic of the normal reproductive action of the machine, is effected continuously in a certain direction during a part of the reproduction. If the model and work are regarded as divided into corresponding series of thin laminae or strips (herein called "differential elements") all parallel to the direction of this additional movement, the corresponding elements in the work will then appear in positions shifted relatively to those of their prototypes in the model; that is, each will be slid a little along its neighbor. Thus the side profile of a last or pattern produced from a given model can be varied by such a shifting of differential elements in a vertical direction.

In the machine illustrated in Patent No. 1,520,075 the model is moved parallel to its length and width independently, by means of cams. The machine shown in Patent No. 1,807,195 is considerably simpler, but has dealt with entire success with the practical problems arising in the pattern grading shop, where the broader capability of the former machine is unnecessary. In both these machines the desired distortion of the normal pantographic reproduction can be effected at any selected portions of the work.

It is a principal object of the present invention to improve still further the two machines just mentioned without sacrificing any of their advantages. The invention will be better understood from a brief consideration of one specific problem, the solution of which it simplifies. Suppose that it is desired to cut a 5B half pattern (that is, a pattern which will cover one side of a last) from a 4B model half pattern, and that the toe spring difficulty is to be corrected by dropping the shank portion gradually from the ball to the heel breast portions, by shifting one of the four primary instrumentalities widthwise while this portion of the pattern is being formed. Next, consider the problem of generating a 6B from the 4B. In this case the rate of the shifting movement should be twice as great as it was in the former case, since the toe spring difficulty found in ordinary grading is substantially proportional to the accretion produced by the magnification. In accordance with the present invention, this shifting movement is governed by the length grading movement in the machine. This length grading

movement is twice as great in the case of a 6B as in the case of a 5B, and therefore the shifting movement mechanism need not be changed in adjustment. A proper adjustment, once found, can be maintained unchanged throughout the production of an entire line of B patterns.

More broadly stated, the present invention contemplates the production of a relative shifting movement of two of the primary instrumentalities of a pattern copying machine in one direction (for example, parallel to the width) by a mechanism which is driven or controlled by the relative movement of two actually moving primary instrumentalities (for example, in a transverse direction or parallel to the length), instead of producing the shifting movement in the one direction by the absolute movement of one instrumentality alone. Thus the shifting movement broadly stated can be made proportional to the graded change in the dimensions of the work, as it should be, without any change in the adjustment of the shifting mechanism. In the illustrated machine the shifted instrumentality is the tool, and the shifting mechanism is driven by the length grading relative movement of the model follower and tool carriages.

An important feature of the invention consists in a machine in which the shifting mechanism in one dimension is driven by a relative grading movement of two parts in the transverse dimension.

Another important feature of the invention resides in an improved length grading mechanism. The matter of center grading may be taken as an illustration of the class of problems which may be dealt with by this means.

Many women's oxford shoes have uppers from the vamp and instep portions of which small pieces have been cut to form an ornamental pattern. Such patterns are cut in the leather upper by means of a die similar to a clicking machine die. It is impracticable to provide a different die for each size and width because of the expense involved and it is necessary to cut this ornamental pattern on the entire line of uppers with only a few dies. It is inadvisable therefore, in many cases, to grade that part of the upper which covers the upper part of the foot in the same way as its rear and lower portions, because the died-out

patterns will not fit the lines of the upper properly, the die being made to fit the lines of a different size. This difficulty has given rise to the practice of center grading. Suppose, for example, that an entire half pattern is to be graded by this method. The cutting will begin at the upper end of the heel, and will proceed down the heel and around the bottom, the grading mechanisms being used in the ordinary way. In coming back to the starting point along the top edge the length grader will be set on center while the area covered by the died-out portion is being passed.

length grader will be set on center while the area covered by the died-out portion is being passed. This makes it fit the die. These parts, as so far described, are of well known construction. When the model wheel has reached the starting point on the model the cutter will not have reached the corresponding point on the work since the bottom has been length graded and part of the top has not, and the cutting has to be finished empirically.

In order to deal with this and similar difficulties, I have provided an improved grading mechanism, herein shown as a length grading mechanism, in which the length grading factor can be

substantially changed, in order, for example, to make up the loss in length grade suffered in passing a died-out portion of a pattern.

The mechanism provided for effecting this result is similar in many respects to that provided for effecting the laminar shifting movement already dealt with. It can be set into and out of operation at any time by the operator to effect a discontinuous change in the length grading factor. As in the former case, it is operated by the relative movement of two of the carriages in the machine, differing, however, in that the anomalous movement of that principal instrumentality produced by it (herein shown as the cutter) is in the same direction as the relative movement of the carriages which produces it.

These and other features of the invention comprising certain combinations and arrangements of parts will be apparent from the following description of a preferred embodiment of the invention shown in the drawings, in which

Fig. 1 is a plan view of the machine;

Fig. 2 is a detail of the grading mechanism;

Fig. 3 is a partial cross-section of the width grading basket; and

Fig. 4 is a diagram illustrating the grading mechanism.

The main frame 10 of the machine is provided with tracks 12 extending widthwise, on which a carriage or frame 14 slides on rollers 16. The frame 14 has tracks 18, 20 extending lengthwise of the machine on which two similarly moving carriages 22, 24 are arranged to slide on rollers 26. The carriage 24 is provided with tracks 28, 30 extending widthwise of the machine on which slides a carriage 30. The carriage 22 carries the model wheel 32, and the carriage 30 carries the cutting tool 34. This arrangement of the sliding carriages permits the model wheel 32 to be moved around the edge of a pattern mounted on the pattern holder 36, on the frame 10, and a length grading mechanism connecting the carriages 22, 24 and a width grading mechanism connecting the carriages 24, 30 cause similar movements of the tool 34 around a work piece mounted on a table 38 on the frame 10. All this mechanism, except novel features in connection with the grading mechanism, which will be described, is well known.

The length grading mechanism comprises a length grading lever 40 pivoted at 42 on the carriage 22. The rear end of the lever is pivoted at 44 on a slide 46 moving on a guide 47 on the carriage 14. The other end of the lever has a slotted segment 48 extending both sides of the pivot 42, in which a basket 50, which will be described more in detail below, is adjustably mounted. This basket and the carriage 24 are connected by a link 52. This mechanism, as so far described, is all well known, and causes the carriages 22, 24 to move at a substantially constant velocity ratio along the track 18, when the carriage 22 is driven by the operator, thus effecting the length graded out length grading it. These parts, as so far described, are of well known construction.

The width grading lever 54 is pivoted at 56 on the carriage 24. Its end 58 is pivoted on a slide 60 which runs along the under side of an elevated bar 62, which is a part of the frame 10. The other end of the lever is slotted at 64 and is provided with an adjustable basket 65 linked to the carriage 30 by a link 66. This construction, as so far described, is well known. It should be noticed that the carriage 22 and model wheel 32 have exactly the same movement at all times;

that the carriage 30 and tool 34 have the same movement at all times; and that the carriage 24, carriage 30 and tool 34 have the same movement to the right or left (Fig. 1) at all times.

5 The basket comprises a block 68 (Fig. 2) sliding in the slot 64. On this block is pivoted a bell crank 70 (Figs. 2 and 3) having an integral slotted arc 72 on its upper face. A block 74 is adjustable in this slot and is pivotally linked by 10 a link 76 to the link 66, which has its end 78 formed as a slide, running on a tongue 80 pivoted on the block 68 about the pivotal axis of the bell crank 70. If the block 74 be adjusted in the slot 72 so that it is in alignment with the pivotal axis 15 of the bell crank 70, rotation of the bell crank 70 has no effect on the link 66 and the carriage 30; but if it be anywhere else in the slot, its movement will impart a movement to the link 66 in addition to any regular width grading movement 20 imparted to it by the width grading lever due to the adjustment of the block 68 off the center 56. This additional movement alters the effective length of the link 66, this effective length being the distance from the pivot connecting the 25 link to the carriage 30 to the pivot in the block 68.

The movement of the bell crank is accomplished by a link 82 pivoted to its arm and to a block 84 adjustable in a slotted member 86, which is pivoted on the axis 56. The member 86 is essentially a bell crank and is rotatable by a link 30 88 pivoted to the carriage 22. Therefore, the differential movement of the carriages in length grading will turn the member 86 and consequently the bell crank 70 which, through the links 76 and 66 and carriage 30, will move the cutter 34 in the widthwise direction. This movement, with 35 any given adjustment, is obviously substantially proportional to the length grade. In other words, if this lateral shifting of the cutter be put into 40 operation over a predetermined portion of a size 4 model, the total shift in the case of a 6 graded from this model will be twice as great as in the case of a 5 graded from the model with the same adjustment of the shifting mechanism.

45 The shifting movement is started and stopped as follows: A pin 90 is provided, by means of which the member 86 and the width grading lever 54 can be rigidly locked together, and the link 88 has a telescope joint 92 with a clamp which, 50 when loosened, permits the two parts of the link to slide on each other. When the pin 90 is out and the clamp 92 tight, the shifting mechanism is operative; when the pin 90 is in and the clamp 55 loose, it is inoperative and the width grader acts in the regular way. The mechanism can thus be started and stopped at any time.

Fig. 3 shows the details of the basket. The slot 64 has a lower dovetailed portion and an upper channeled portion at one side. The block 68 60 rides in the channeled portion above the dovetail. A spindled block 94 rides in the dovetailed portion, the spindle passing up through the block 68. At the top of the block 68 is a knurled nut 96 which draws the block 94 up into the dovetail and clamps the block 68 in adjusted position.

65 The bell crank 70 is pivoted on a round boss 97 on the nut 96.

The construction of the length grading lever basket 50 is similar to that just described and its 70 parts have been marked by primed corresponding numerals. The link 52 is here made in two relatively sliding parts, like the link 66, and its effective length is changed by the rotation of the bell crank 70'. The member 86' is swung by the 75 link 88' which connects it to the carriage 24.

By this mechanism, a lengthwise movement of the cutter 34, in addition to the movement characteristic of ordinary operation of the machine, can be effected whenever desired by removing the pin 90' and setting the clamp 92'. It is produced by and is substantially proportional to the ordinary differential length grading movement of the carriages 22, 24. Thus, the length grading ratio can be varied at desired parts of the work, without causing any jog in the periphery thereof.

The machine has so many overlying parts that a diagrammatic view (Fig. 4) has been provided. This is not to be understood as drawn to scale. Its object is merely to make the construction clear.

The illustrated mechanism comprising the bell crank 70 for moving the cutter widthwise may be called a shifting mechanism or an offsetting mechanism. By this is meant, broadly, a mechanism for causing a movement of one primary instrumentality in the machine, or a relative movement of two of them, in a certain direction, the mechanism being operated by a movement of one of the instrumentalities or a relative movement of two of them in a direction perpendicular to that of the first-mentioned movement. That is, a purely lengthwise movement effected by the operator will cause a widthwise movement of the sort described as "offsetting" or "shifting". This phenomenon is to be understood as occurring in addition to the ordinary reproductive movement, if any, then occurring in the machine, and the result in the work is a compound of the two. The movement effected by an offsetting or shifting mechanism is independent of grading movements. Both types of movement take place independently.

The illustrated improved length grading mechanism comprising the bell crank 70' is not a shifting or offsetting mechanism, as defined herein, since the movement it produces in addition to the regular grading movement is in the same direction as the movement which produces it. The term "displacing mechanism" or the like has been used in certain claims as generic to these two mechanisms.

Having described my invention, what I claim as new and desire to secure by Letters Patent of the United States is:

1. In a pattern reproducing machine, four primary instrumentalities, viz., a model holder, a work holder, a model follower holder and a tool holder, grading mechanism connecting them constructed and arranged to produce actual movement of and relative movement between two of them to reproduce a model in the model holder in a work piece in the work holder, and an additional driving connection located between the last two said instrumentalities for imparting to one of said four instrumentalities an additional reproductive movement in a certain direction, said last named mechanism being driven by relative movement of the two said relatively moving primary instrumentalities while both are actually moving.

125

130

135

140

2. In a pattern reproducing machine, four primary instrumentalities, viz., a model holder, a work holder, a model follower holder and a tool holder, grading mechanism connecting them for relative movement to reproduce a model in the model holder in a work piece in the work holder, mechanism for imparting to one of said instrumentalities an additional reproductive movement in a certain direction, said last-named mechanism being driven by relative movement of 145

145

150

- two said primary instrumentalities while both are actually moving, and means for putting said mechanism into and out of operation at any desired time during the reproduction of a work piece. 5
3. In a pattern copying machine, four primary instrumentalities, viz., a model holder, a work holder, a model wheel and a tool, grading mechanism connecting them constructed and arranged to effect actual movement of, and differential movement between, two of said primary instrumentalities in a certain direction to reproduce the model pantographically in the work, and an offsetting mechanism connecting the two differentially moving instrumentalities for effecting an offsetting movement of one of said four primary instrumentalities, said offsetting mechanism comprising a pivoted lever, an adjustable connection between the lever and the offset instrumentation, whereby the swinging of the lever will offset the instrumentation, and means for swinging the lever operated by the said differential movement. 10
4. In a pattern copying machine, four primary instrumentalities, viz., a model holder, a work holder, a model wheel and a tool, grading mechanism connecting them constructed and arranged to effect differential movement between two said primary instrumentalities while they both are actually moving to reproduce the model pantographically in the work, and a displacing mechanism connecting the two differentially moving instrumentalities and comprising a slide for effecting a displacing movement of one of said four primary instrumentalities in addition to its normal grading movement. 15
5. In a pattern reproducing machine, four primary instrumentalities, viz., a model worker, a work holder, a model follower holder and a tool holder, arranged for relative movement to reproduce a model in the model holder in a work piece in the work holder, grading levers for controlling the relative movement, a movable member operatively connected between two of said primary instrumentalities both of which actually move during the reproduction, and driven by relative reproductive movement of the two last mentioned primary instrumentalities, and a connection between said member and one of said four primary instrumentalities whereby said last mentioned primary instrumentality is given an additional reproductive movement. 20
6. In a pattern reproducing machine, four primary instrumentalities, viz., a model holder, a work holder, a model follower holder and a tool holder, arranged for relative movement to reproduce a model in the model holder in a work piece in the work holder, grading levers for controlling the relative movement, a movable member operatively connected between two of said primary instrumentalities both of which actually move during the reproduction, and driven by relative reproductive movement of the two last mentioned primary instrumentalities, and a connection between said member and one of said four primary instrumentalities whereby said last mentioned primary instrumentality is given an additional reproductive movement, said movable member being operable at any selected part of the reproduction at the will of the operator. 25
7. In a pattern reproducing machine, four primary instrumentalities, viz., a model holder, a work holder, a model follower holder and a tool holder, grading mechanism connecting them for relative movement to reproduce a model in the model holder in a work piece in the work holder, and mechanism for imparting to one of said instrumentalities an additional reproductive movement in a certain direction, said last-named mechanism being driven by relative movement of two said primary instrumentalities while both are actually moving and being also operable or inoperable at any time at the will of the operator. 30
8. In a pattern copying machine, four primary instrumentalities, viz., a model holder, a work holder, a model wheel and a tool, grading mechanism connecting them constructed and arranged to effect differential movement between two actually moving said primary instrumentalities in a certain direction to reproduce the model pantographically in the work, and a shifting mechanism connecting the two differentially moving instrumentalities for effecting a shifting movement of one of said four primary instrumentalities in a direction transverse to that of the said differential movement. 35
9. In a pattern copying machine, four primary instrumentalities, viz., a model holder, a work holder, a model wheel and a tool, grading mechanism connecting them constructed and arranged to effect differential movement between two actually moving said primary instrumentalities in a certain direction to reproduce the model pantographically in the work, and a shifting mechanism connecting the two differentially moving instrumentalities constructed and arranged to effect a shifting movement of one of said two primary instrumentalities in a direction transverse to that of the said differential movement. 40
10. In a pattern copying machine, four primary instrumentalities, viz., a model holder, a work holder, a model wheel and a tool, grading mechanism connecting them constructed and arranged to effect differential movement in a certain direction between two of said primary instrumentalities while they are actually moving in the said certain direction to reproduce the model pantographically in the work, and a shifting mechanism connecting the two differentially moving instrumentalities and comprising a slide for effecting a shifting movement of one of said differentially moving instrumentalities in a direction transverse to that of the said differential movement. 45
11. In a pattern copying machine, four primary instrumentalities, viz., a model holder, a work holder, a model wheel and a tool, a model wheel carriage and a tool carriage, grading mechanism connecting said carriages constructed and arranged to reproduce the model pantographically in the work, and mechanism operated by the grading mechanism, while acting in a certain direction, constructed and arranged to effect a shifting movement of one of said primary instrumentalities in a direction transverse to the said direction of action of the grading mechanism, said shifting movement being in addition to the movement of the shifted instrumentality characteristic of the normal reproductive action of the machine. 50
12. In a pattern reproducing machine, four primary instrumentalities, viz., a model holder, a work holder, a model follower holder and a tool holder, grading mechanism connecting them for relative movement to reproduce a model in the model holder in a work piece in the work holder, and mechanism interconnecting two actually moving said instrumentalities and operated by relative movement thereof in a certain direction for imparting to one of said four primary instrumentalities a reproductive movement in a di- 55

- rection transverse to the said certain direction.
13. In a pattern reproducing machine, four primary instrumentalities, viz., a model holder, a work holder, a model follower holder and a tool holder, grading mechanism interconnecting them for relative movement to reproduce a model in the model holder in a work piece in the work holder, and mechanism interconnecting two of said instrumentalities for actually and relatively moving them, said last-named mechanism comprising means operated by relative translational movement of the two last-mentioned instrumentalities for imparting to one of said two primary instrumentalities a reproductional movement in a direction transverse to the last mentioned relative movement.
14. In a pattern reproducing machine, four primary instrumentalities, viz., a model holder, a work holder, a model follower holder and a tool holder, grading mechanism interconnecting them for relative movement to reproduce a model in the model holder in a work piece in the work holder, mechanism interconnecting two actually moving said instrumentalities and operated by relative translational movement thereof for imparting to one of said four primary instrumentalities a reproductional movement in a direction transverse to the last mentioned relative movement, and means for rendering said last-named mechanism operative and inoperative at will.
15. In a pattern reproducing machine, four primary instrumentalities, viz., a model holder, a work holder, a model follower holder and a tool holder, grading mechanism interconnecting them for relative movement to reproduce a model in the model holder in a work piece in the work holder, mechanism interconnecting two said instrumentalities while actually moving to reproduce the model in the work and operated by relative translational movement thereof for imparting to one of said four primary instrumentalities a reproductional movement in a direction transverse to that of the last mentioned relative movement, and means for putting said last-named mechanism into and out of operation at any desired time during the reproduction of a work piece.
16. In a pattern reproducing machine, four primary instrumentalities, viz., a model holder, a work holder, a model follower holder and a tool holder, grading mechanism interconnecting them for relative movement to reproduce a model in the model holder in a work piece in the work holder, mechanism interconnecting two such instrumentalities as actually move during the reproduction, and operated by relative movement thereof in a certain direction for imparting to one of said two primary instrumentalities a reproductional movement in a direction transverse to the last mentioned relative movement, and means for putting said last-named mechanism into and out of operation at any desired time during the reproduction of a work piece.
17. In a pattern reproducing machine, four primary instrumentalities, viz., a model holder, a work holder, a model follower holder and a tool holder, arranged for relative movement to reproduce a model in the model holder in a work piece in the work holder, grading levers for controlling the relative movement, a movable member operatively connected between two of said primary instrumentalities both of which actually move during the reproduction, and driven by relative translational reproductional movement of the two last mentioned primary instrumentalities, and a connection between said member and one of said four primary instrumentalities whereby said last mentioned primary instrumentality is given a reproductional movement transverse to the said relative reproductional movement.
18. In a pattern copying machine, four primary instrumentalities, viz., a model holder, a work holder, a model wheel and a tool, grading mechanism connecting them constructed and arranged to effect actual movement of, and differential movement between, two of said primary instrumentalities in a certain direction to reproduce the model pantographically in the work, and a shifting mechanism connecting the two differentially moving instrumentalities constructed and arranged to effect a shifting movement of one of said four primary instrumentalities in a direction transverse to that of the said differential movement, said shifting mechanism comprising a pivoted lever, an adjustable connection between the lever and the shifted instrumentality, whereby the swinging of the lever will shift the shifted instrumentality, and means for swinging the lever operated by the said differential movement.
19. In a pattern copying machine, four primary instrumentalities, viz., a model holder, a work holder, a model wheel and a tool, grading mechanism connecting them constructed and arranged to effect actual movement of, and differential movement between, two of said primary instrumentalities in a certain direction to reproduce the model pantographically in the work, and a shifting mechanism connecting the two differentially moving instrumentalities constructed and arranged to effect a shifting movement of one of said primary instrumentalities in a direction transverse to that of the said differential movement, said shifting mechanism comprising a pivoted lever, the pivot of which is constrained against movement in the said certain direction relatively to one of the differentially moving instrumentalities, a connection between the lever and the other of the differentially moving instrumentalities whereby the said differential movement swings the lever, and a connection between the lever and the shifted instrumentality whereby the swinging of the lever shifts that instrumentality.
20. In a pattern copying machine, four primary instrumentalities, viz., a model holder, a work holder, a model wheel and a tool, grading mechanism connecting them constructed and arranged to effect differential movement between two of said primary instrumentalities while they are actually moving in a certain direction to reproduce the model pantographically in the work, and a shifting mechanism connecting the two differentially moving instrumentalities constructed and arranged to effect a shifting movement of one of said primary instrumentalities in a direction transverse to that of the said differential movement, said shifting mechanism comprising a rod fastened to one of the differentially moving instrumentalities and mechanism on the other operated by the rod, said mechanism comprising a lever connected to the shifted instrumentality.
21. In a pattern reproducing machine, four primary instrumentalities, viz., a model holder, a work holder, a model follower holder and a tool holder, arranged for relative movement, a grading mechanism connecting them and controlling the relative movement to reproduce a model in the model holder in a work piece in the work holder, an additional member operatively con-

- necting two of such instrumentalities as actually move translationally during the reproduction, and a second member operated by said additional connecting member and connected to a said primary instrumentality, to impart to the last named primary instrumentality a reproductive movement transverse to the direction of said actual movement.
22. In a pattern reproducing machine, four primary instrumentalities, viz., a model holder, a work holder, a model follower holder and a tool holder, arranged for relative movement, grading levers for controlling the relative movement to reproduce a model in the model holder in a work piece in the work holder; an additional member operatively connecting two of said primary instrumentalities, both of which primary instrumentalities actually move in parallel directions at different speeds in the reproduction, and a swinging member operated by said additional member and connected to one of said two primary instrumentalities, to impart to said last mentioned primary instrumentality a reproductive movement transverse to said parallel directions.
23. In a pattern reproducing machine, four primary instrumentalities, viz., a model holder, a work holder, a model follower holder and a tool holder, grading mechanism interconnecting two of them arranged, when one is moved in a certain direction, to cause the other to move in a parallel direction at a different velocity, and a movable member connected with both of said two last named primary instrumentalities and arranged to drive one of them in a direction transverse to the said parallel direction, said movable member being itself driven by the said relative movement of the two last named primary instrumentalities.
24. In a pattern reproducing machine, four primary instrumentalities, viz., a model holder, a work holder, a model follower holder and a tool holder, two carriages supporting two of said instrumentalities respectively and arranged for actual movement in a certain direction, a grading mechanism connecting the carriages for controlling their relative movement parallel to the said direction, and a lever pivotally supported by one of the carriages and connected to the other, whereby the relative movement of the carriages moves the lever; the lever being also connected to one of the said four instrumentalities other than the one supported by the last named carriage.
25. In a pattern reproducing machine, four primary instrumentalities, viz., a model holder, a work holder, a model follower holder and a tool holder, two carriages supporting two of said instrumentalities respectively and arranged for actual movement in a certain direction, a grading mechanism connecting the carriages for controlling their relative movement parallel to the said direction, and a lever pivotally supported by one of the carriages and connected to the other, whereby the relative movement of the carriages moves the lever at a rate substantially proportional to the said relative movement, the lever being also adjustably connected to one of the said four instrumentalities other than the one supported by the last named carriage, in order to vary the ratio of proportionality.
26. In a pattern reproducing machine, four primary instrumentalities, viz., a model holder, a work holder, a model follower holder and a tool holder, two carriages supporting two of said instrumentalities respectively and arranged for actual movement in a certain direction, a grading mechanism connecting the carriages for controlling their relative movement parallel to the said direction, and a lever pivotally supported by one of the carriages and connected to the other, whereby the relative movement of the carriages moves the lever, the lever being also connected to one of the said four instrumentalities.
27. In a pattern reproducing machine, four primary instrumentalities, viz., a model holder, a work holder, a model follower holder and a tool holder, two carriages supporting two of said instrumentalities respectively and arranged for actual movement in a certain direction, a grading mechanism connecting the carriages for controlling their relative movement parallel to the said direction, and a lever pivotally carried by one of the carriages and connected to the other, whereby the relative movement of the carriages moves the lever, the lever being also connected to that one of the four primary instrumentalities which is supported on the carriage which carries the lever.
28. In a pattern reproducing machine, four primary instrumentalities, viz., a model holder, a work holder, a model follower holder and a tool holder, two carriages arranged to move in a certain direction, a grading mechanism arranged to control their relative movement, and a member operated by the relative movement of the carriages in the said certain direction, and arranged, when operated, to drive one of said primary instrumentalities in a direction at right angles to said certain direction.
29. In a pattern reproducing machine, four primary instrumentalities, viz., a model holder, a work holder, a model follower holder and a tool holder, two carriages arranged to move in a certain direction, a grading mechanism arranged to control their relative movement, and a member operated by the relative movement of the carriages in the said certain direction, the movement of said member, when operated, being proportional to said relative movement, the member being also arranged, when operated, to drive one of said primary instrumentalities in a direction at right angles to said certain direction.
30. In a machine of the class described, a carriage arranged to move in a certain direction, a pair of carriages mounted thereon and arranged to move in a direction transverse to said direction, a fourth carriage mounted on one of said pair for movement thereon in said certain direction, a grading mechanism connecting the pair of carriages to control their relative movement in the transverse direction, and a bell crank carried by one of said pair and having its arms connected to the other of the pair and to the fourth carriage, respectively.
31. In a machine of the class described, a carriage arranged to move in a certain direction, a pair of carriages mounted thereon and arranged to move in a direction transverse to said direction, a fourth carriage mounted on one of said pair for movement thereon in said certain direction, a grading mechanism connecting the pair of carriages to control their relative movement in the transverse direction, a bell crank having one arm connected to the fourth carriage, and a link connecting the other arm of the bell crank to that carriage of the pair on which the fourth carriage is not mounted.
32. In a pattern reproducing machine, four primary instrumentalities, viz., a model holder, a work holder, a model follower holder and a tool holder, grading mechanism interconnecting

- two of them arranged, when one is moved in a certain direction, to cause the other to move in a parallel direction at a different velocity, and a bell crank having one arm arranged to drive 5 one of said two last named primary instrumentalities in a direction transverse to said certain direction and having the other arm connected to the other. 80
33. In a pattern reproducing machine, four primary instrumentalities, viz., a model holder, a work holder, a model follower holder and a tool holder, grading mechanism interconnecting two of them arranged, when one is moved in a certain direction, to cause the other to move in a parallel direction at a different velocity, a bell crank having one arm adjustably connected to one of said two last named primary instrumentalities to drive the same in a direction transverse to the said certain direction, and a link 15 connecting the other arm of the bell crank to the other of said two primary instrumentalities, to drive the bell crank. 85
34. In a machine of the class described, a carriage arranged to move in a certain direction, a pair of carriages mounted thereon and arranged to move in a direction transverse to said direction, a fourth carriage mounted on one of said pair for movement thereon in said certain direction, a length grading mechanism connecting the pair of carriages to control their relative movement in the transverse direction, a width grading mechanism connecting the fourth carriage to that carriage of the pair on which it is mounted, to control the relative movement of these carriages in the said certain direction, a movable arm forming a part of the width grading connection whereby its effective length can be altered, and means for moving the arm to alter the said length, controlled by the relative movement of the said pair of carriages in the transverse direction. 90
35. In a machine of the class described, a carriage arranged to move in a certain direction, a pair of carriages mounted thereon and arranged to move in a direction transverse to said direction, a fourth carriage mounted on one of said pair for movement thereon in said certain direction, a length grading mechanism connecting the pair of carriages to control their relative movement in the transverse direction, a width grading mechanism connecting the fourth carriage to that carriage of the pair on which it is mounted, to control the relative movement of these carriages in the said certain direction, and a bell crank forming a part of the width grading connection, having one of its arms connected to one of the two carriages connected thereby, whereby the effective length of the width grading connection can be altered, and having its other arm driven by the other carriage of the pair. 95
36. In a machine of the class described, a carriage arranged to move in a certain direction, a pair of carriages mounted thereon and arranged to move in a direction transverse to said direction, a fourth carriage mounted on one of said pair for movement thereon in said certain direction, a length grading mechanism connecting the pair of carriages to control their relative movement in the transverse direction, a width grading mechanism connecting the fourth carriage to that carriage of the pair on which it is mounted, to control the relative movement of these carriages in the said certain direction, a bell crank forming a part of the width grading connection, having one of its arms connected to one of the two carriages of the pair on which it is mounted, to control the relative movement of these carriages in the said certain direction, a bell crank forming a part of the width grading connection, having one of its arms connected to one of the two carriages connected thereby, whereby the effective length of the width grading connection can be altered, and having its other arm driven by the other carriage of the pair. 100
37. In a pattern reproducing machine, four primary instrumentalities, viz., a model holder, a work holder, a model follower holder and a tool holder, grading mechanism interconnecting two of them arranged, when one is moved in a certain direction, to cause the other to move in a parallel direction at a different velocity, a bell crank having one arm adjustably connected to one of said two last named primary instrumentalities to drive the same in a direction transverse to the said certain direction, a link connecting the other arm of the bell crank to the other of said two primary instrumentalities, to drive the bell crank, means for locking the bell crank against rotary movement, and a telescope joint in the said link for rendering the link inoperative to drive the bell crank. 105
38. In a machine of the class described, a carriage arranged to move in a certain direction, a pair of carriages mounted thereon and arranged to move in a direction transverse to said direction, a fourth carriage mounted on one of said pair for movement thereon in said certain direction, a length grading mechanism connecting the pair of carriages to control their relative movement in the transverse direction, a width grading mechanism connecting the fourth carriage to that carriage of the pair on which it is mounted, to control the relative movement of these carriages in the said certain direction, a bell crank lever carried by one of the pair of carriages, and forming a part of the width grading connection, constructed and arranged to alter the effective length of the connection, a link connecting the bell crank to the other carriage of said pair, and arranged to drive the bell crank by the relative movement of the pair of carriages, means for locking the bell crank to the carriage on which it is mounted, and a joint in the link whereby the link may be made inoperative to drive the bell crank. 110
39. In a pattern reproducing machine, four primary instrumentalities, viz., a model holder, a work holder, a model follower holder and a tool holder, grading mechanism connecting them for relative movement to reproduce a model in the model holder in a work piece in the work holder, and mechanism for imparting to one of said instrumentalities an additional reproductive movement in a certain direction, said last-named mechanism being driven by the relative movement of two such primary instrumentalities as actually move in the said certain direction. 115
40. In a pattern reproducing machine, four primary instrumentalities, viz., a model holder, a work holder, a model follower holder and a tool holder, grading mechanism connecting them for relative movement to reproduce a model in the model holder in a work piece in the work holder, mechanism for imparting to one of said instrumentalities an additional reproductive movement in a certain direction, said last-named mechanism being driven by the relative movement of two said primary instrumentalities while they are actually moving in the said certain direction, and means for putting said mechanism into and out of operation at any desired time during the reproduction of a work piece. 120
41. In a pattern reproducing machine, four primary instrumentalities, viz., a model holder, a work holder, a model follower holder and a tool holder, grading mechanism connecting them for relative movement to reproduce a model in the model holder in a work piece in the work holder, mechanism for imparting to one of said instrumentalities an additional reproductive movement in a certain direction, said last-named mechanism being driven by the relative movement of two such primary instrumentalities as actually move in the said certain direction. 125
42. In a pattern reproducing machine, four primary instrumentalities, viz., a model holder, a work holder, a model follower holder and a tool holder, grading mechanism connecting them for relative movement to reproduce a model in the model holder in a work piece in the work holder, mechanism for imparting to one of said instrumentalities an additional reproductive movement in a certain direction, said last-named mechanism being driven by the relative movement of two said primary instrumentalities while they are actually moving in the said certain direction, and means for putting said mechanism into and out of operation at any desired time during the reproduction of a work piece. 130
43. In a pattern reproducing machine, four primary instrumentalities, viz., a model holder, a work holder, a model follower holder and a tool holder, grading mechanism connecting them for relative movement to reproduce a model in the model holder in a work piece in the work holder, mechanism for imparting to one of said instrumentalities an additional reproductive movement in a certain direction, said last-named mechanism being driven by the relative movement of two such primary instrumentalities as actually move in the said certain direction. 135
44. In a pattern reproducing machine, four primary instrumentalities, viz., a model holder, a work holder, a model follower holder and a tool holder, grading mechanism connecting them for relative movement to reproduce a model in the model holder in a work piece in the work holder, mechanism for imparting to one of said instrumentalities an additional reproductive movement in a certain direction, said last-named mechanism being driven by the relative movement of two said primary instrumentalities while they are actually moving in the said certain direction, and means for putting said mechanism into and out of operation at any desired time during the reproduction of a work piece. 140
45. In a pattern reproducing machine, four primary instrumentalities, viz., a model holder, a work holder, a model follower holder and a tool holder, grading mechanism connecting them for relative movement to reproduce a model in the model holder in a work piece in the work holder, mechanism for imparting to one of said instrumentalities an additional reproductive movement in a certain direction, said last-named mechanism being driven by the relative movement of two such primary instrumentalities as actually move in the said certain direction. 145
46. In a pattern reproducing machine, four primary instrumentalities, viz., a model holder, a work holder, a model follower holder and a tool holder, grading mechanism connecting them for relative movement to reproduce a model in the model holder in a work piece in the work holder, mechanism for imparting to one of said instrumentalities an additional reproductive movement in a certain direction, said last-named mechanism being driven by the relative movement of two said primary instrumentalities while they are actually moving in the said certain direction, and means for putting said mechanism into and out of operation at any desired time during the reproduction of a work piece. 150

41. In a pattern reproducing machine, four primary instrumentalities, viz., a model holder, a work holder, a model follower holder and a tool holder, grading mechanism interconnecting them for relative movement to reproduce a model in a lever pivoted on one of the carriages and connected to the other, whereby the relative movement of the carriages moves the lever, the lever having another connection between it and one of the said four instrumentalities. 80
42. In a pattern reproducing machine, four primary instrumentalities, viz., a model holder, a work holder, a model follower holder and a tool holder, arranged for relative movement in a direction parallel to the last mentioned relative movement. 85
43. In a pattern reproducing machine, four primary instrumentalities, viz., a model holder, a work holder, a model follower holder and a tool holder, arranged for relative movement, a grading mechanism connecting them and controlling the relative movement to reproduce a model in the model holder in a work piece in the work holder, an additional member connecting two actually moving said instrumentalities, and a second member operated by said additional connecting member and connected to a said primary instrumentality, to impart to the last named primary instrumentality a reproduction movement in the direction of said actual movement. 90
44. In a pattern reproducing machine, four primary instrumentalities, viz., a model holder, a work holder, a model follower holder and a tool holder, arranged for relative movement to reproduce a model in the model holder in a work piece in the work holder, grading levers for controlling the relative movement, a movable member connected to two said primary instrumentalities both of which actually move during the reproduction and driven by the said relative reproduction movement of the two last mentioned primary instrumentalities, and a connection between said member and one of said four primary instrumentalities whereby said last mentioned primary instrumentality is given an additional reproduction movement in the direction of said relative reproduction movement. 95
45. In a pattern reproducing machine, four primary instrumentalities, viz., a model holder, a work holder, a model follower holder and a tool holder, grading mechanism interconnecting two of them arranged, when one is moved in a certain direction, to cause the other to move in a parallel direction at a different velocity, and a bell crank having one arm arranged to drive one of said two last named primary instrumentalities in the said certain direction, and having its other arm connected to the other. 100
46. In a pattern reproducing machine, four primary instrumentalities, viz., a model holder, a work holder, a model follower holder and a tool holder, grading mechanism interconnecting two of them arranged, when one is moved in a certain direction, to cause the other to move in a parallel direction at a different velocity, a bell crank carried by one of the last named two primary instrumentalities having one arm connected to the other of said two last named primary instrumentalities to drive the same in the said certain direction, and a connection between the other arm of the bell crank and the first named of said two primary instrumentalities, said connection comprising a link. 105
47. In a pattern reproducing machine, four primary instrumentalities, viz., a model holder, a work holder, a model follower holder and a tool holder, two carriages arranged to move in a certain direction, and each carrying one of the instrumentalities, a grading mechanism arranged to control their relative movement, and a member operated by the relative movement of the carriages in the said certain direction, and arranged, when operated, to drive one of said primary instrumentalities in the said direction. 110
48. In a pattern reproducing machine, four primary instrumentalities, viz., a model holder, a work holder, a model follower holder and a tool holder, two carriages arranged to move in a certain direction, a grading mechanism arranged to control their relative movement, and a member operated by the relative movement of the carriages in the said certain direction, the movement of said member, when operated, being proportional to said relative movement, the member being also arranged, when operated, to drive one of said primary instrumentalities in the said direction. 115
49. In a machine of the class described, a carriage arranged to move in a certain direction, a pair of carriages mounted thereon and arranged to move in a direction transverse to said direction, a grading mechanism connecting the pair of carriages to control their relative movement in the transverse direction, the grading mechanism comprising a link extending between the pair of carriages, means for automatically altering the effective length of the link during the production of a work piece, and a manually adjustable means for setting the said length 120 altering means into operation at the desired time. 125
50. In a pattern copying machine for reproducing a plane model in a plane work piece, four elements, viz., a model holding means, a work holding means, a model follower and a tool, and a grading mechanism, operating relatively to a grading axis and parallel to the planes of the model and work, operatively connecting the said elements for reproducing each point of the model in the work by means of relative movements of the said elements, and an offsetting device connected to one of the said elements and operated by the relative movement of two of said four elements which are actually moving parallel to the grading axis during the reproduction, for offsetting the last-named element perpendicularly to the said grading axis to cause the reproduction of a collinear aggregate of points in the model in a line which is not straight in the work. 130
51. In a machine of the class described for reproducing a plane pattern in a plane work piece, four primary instrumentalities, viz., a model holding means, a work holding means, a model following means and a tool, a grading mechanism operating parallel to the planes of the model and work connecting said instrumentalities and arranged to magnify or reduce a model in a work piece, and an offsetting device constructed and arranged to move a said primary instrumentality in a certain direction in said 135 140
52. In a pattern reproducing machine, four primary instrumentalities, viz., a model holder, a work holder, a model follower holder and a tool holder, two carriages supporting two of said instrumentalities respectively and arranged for ac- 145 150

plane, without modifying the grading factor, to cause the reproduction of a collinear aggregate of points in the model non-collinearly in the work, said offsetting device being driven by the relative movement of two of the four primary instrumentalities which are actually moving during the reproduction and comprising means whereby it may be caused to operate only at predetermined portions of the work, the offsetting device being inoperative at other portions of the work.

52. In a machine of the class described, four primary instrumentalities, viz., a model holding means, a work holding means, a model following means and a tool, a grading mechanism operatively connecting them and arranged to magnify or reduce a model in a work piece, and an offsetting device driven by the relative movement of two of the four primary instrumentalities which are actually moving during the reproduction and operating in a fixed plane constructed and arranged, without modifying the grading factor, to effect a displacement, parallel to the said fixed plane, of one of the said primary instrumentalities relatively to the others, in the reproduction of predetermined portions only of the model, such displacement being in addition to the relative movement of the four primary instrumentalities characteristic of pantographic reproduction of the model in the work, and such displacement widthwise of the work, at a point being reproduced, being determined by the lengthwise position respectively of such point.

53. In a machine of the class described for reproducing a plane model in a plane work piece, four primary instrumentalities, viz., a model holding means, a work holding means, a model following means and a tool, a grading mechanism operatively connecting them and operating in planes parallel to the planes of the model and work to magnify or reduce a model in a work piece comprising an offsetting device driven by the relative movement of two of the four primary instrumentalities which are actually moving during the reproduction and constructed and arranged to modify the operative connection to effect a displacement, parallel to a said plane, of one of the said primary instrumentalities relatively to the others, without change in the grading factor, such displacement being in addition to the relative movement of the four primary instrumentalities characteristic of pantographic reproduction of the model in the work, and such displacement lengthwise of the work, at a point being reproduced, being determined by the widthwise position of such point respectively, and means for rendering the offsetting device operative at predetermined points of the work only.

54. In a pattern grading machine, four primary instrumentalities, viz., a model holder, a work holder, a model follower and a tool and grading mechanism arranged to reproduce a model held in the holder in a work piece held

in the work holder, and means for shifting one of the primary instrumentalities in a certain fixed direction, said means being operated by relative movement of two of said primary instrumentalities which are actually moving during the reproduction in a direction transverse to said fixed direction and comprising a driving mechanism and means whereby the driving mechanism may be caused to shift the shifting holder in the said direction or its opposite as desired, at predetermined portions only of the work.

55. In a pattern grading machine, four primary instrumentalities, viz., a model holder, a work holder, a model follower and a tool interconnected and arranged to reproduce a model held in the holder in a work piece held in the work holder, and means for shifting one of the primary instrumentalities in a fixed direction, said means being operated by relative movement of two of said primary instrumentalities which are actually moving during the reproduction, said movement being ancillary to relative movement of the tool and work in a direction transverse to said direction and said means being operable during selected portions only of a reproducing operation.

56. In a pattern grading machine, four primary instrumentalities, viz., a model holder, a work holder, a model follower and a tool connected and arranged for relative movement to reproduce a model lying in a plane, in a work piece lying in a plane, and mechanism for effecting a relative movement between two of the said instrumentalities in a certain direction parallel to one of the said planes, in addition to the relative movement characteristic of the normal reproductive action of the machine, said mechanism being operated by a relative reproductive movement of two of said primary instrumentalities which are actually moving in a direction at right angles to the said certain direction, and means whereby said mechanism may be caused to operate or not at predetermined portions of the work.

57. In a pattern reproducing machine, four primary instrumentalities, viz., a model holder, a work holder, a model follower holder and a tool holder, grading mechanism connecting them constructed and arranged to produce actual movement of and relative movement between two of them to reproduce a model in the model holder in a work piece in the work holder, and a driving connection located between the two said moving instrumentalities for imparting to one of said four instrumentalities an additional reproductive movement in a certain direction, said connection comprising a member movable relatively to one of said two moving instrumentalities and operated by relative movement of the two said moving primary instrumentalities while both are actually moving.

GEORGE F. RYAN.

CERTIFICATE OF CORRECTION.

Patent No. 1,982,764.

December 4, 1934.

GEORGE F. RYAN.

It is hereby certified that error appears in the printed specification of the above numbered patent requiring correction as follows: Page 3, line 125, claim 1, for "reproducting" read reproducing; page 4, line 143, claim 12, for "connecting" read inter-connecting; and page 7, line 127, claim 39, after "holder" insert a comma; and that the said Letters Patent should be read with these corrections therein that the same may conform to the record of the case in the Patent Office.

Signed and sealed this 9th day of July, A. D. 1935.

Bryan M. Battey

(Seal)

Acting Commissioner of Patents.
